UNITED STATES PATENT OFFICE.

WILLIAM G. SLAUSON, OF OLEAN, NEW YORK.

PRINTER'S FURNITURE.

SPECIFICATION forming part of Letters Patent No. 657,254, dated September 4, 1900.

Application filed November 10, 1899. Serial No. 738,516. (No model.)

To all whom it may concern:

Be it known that I, WILLIAM G. SLAUSON, a citizen of the United States, residing at Olean, in the county of Cattaraugus and State 5 of New York, have invented certain new and useful Improvements in Printers' Furniture, of which the following is a specification, reference being had therein to the accompanying drawings.

10 This invention relates to combination or locking furniture for printers' use.

The object of the invention is to produce sets of metallic furniture which shall be adjustable to many positions in filling out or 15 completing forms, so that a large assortment of sizes may be made from a small number of furniture-pieces.

The furniture is made from metal and may 20 be a cheap cast-metal, iron being satisfactory. By preference a set of the furniture will consist of four pieces, of which two or three may be used in combination. Such combination, by changing one piece for another, will give a range of adaptability covering 25 a very wide range.

Figure 1 illustrates a plan of a combination of three of my furniture-pieces. Fig. 2 is a plan of a combination of two pieces, and Fig. 3 a combination of two pieces in the extreme 30 position, one of the pieces being different from the piece of Fig. 2. Fig. 4 is a broken detail section showing engagement of the stops or locking-bolt with the rack. Fig. 5 is a broken perspective of one piece of furniture. Fig. 6 is an edge view showing 35 the wrench-sockets.

The furniture consists of separate metallic pieces, less than type high, and preferably made with marginal ribs and open centers, so that a minimum weight of material may be required, as usual with printers' furniture. All the pieces of a set are beveled or inclined on at least one side and one piece of the combination set is beveled on both sides. As many as half the pieces have rack-teeth on one edge, but are preferably plane on the other, and enough of the pieces are provided with holding-pawls to secure a lock for each combination. The pieces of each set are of the same length, but of different widths. The sets are made of different lengths and may be combined as sets when large blank

spaces are to be filled. For instance, one set of fifteen or sixteen inches length of furniture may be combined with two sets of eight-inch furniture to fill a blank space of sixteen or more inches in length and wider than can be filled by the long furniture. Permutations and combinations will be readily arranged by a person accustomed to impose printing-forms.

Let A, B, C, and BB represent the metal pieces of an ordinary combination set involving this invention. Piece A has the sides A' A² A³ extending in the lines of a rectangle. The fourth side is beveled and provided with teeth A⁴, extending in vertical direction from edge to edge. Piece B has a plane side B' and ends B² and B³ at right angles thereto. On the beveled side B⁴ the furniture-piece has locking-catches b b', held in mortises or sockets in the body of the furniture and having their outer ends beveled and normally projecting slightly beyond the plane of the inclined face, being pressed out by springs b² after the manner of a spring-bolt or door-catch. A loop or band b³, preferably of spring metal, connects the two bolt-heads and serves to draw back these bolts or catches when desirable, either by hand or the application of a lever or handle. As shown more fully in Fig. 4, the spring-pressed bolts or catches are not spaced the same distance apart as are the teeth A⁴, although these spring-bolts are intended to engage such teeth. By unequal spacing one of the bolts b or b' will engage the notch between two teeth A⁴, while the other bolt is pressed back by another tooth of the rack. By a slight shifting of one of the pieces A or B in the direction of its length the bolt b, which engages one of the teeth, will be pressed back, and the other bolt will catch a tooth after a longitudinal movement of either piece less than the width of a tooth A⁴. The pieces B and BB have recesses R about semicircular in form and extending into the body of the furniture far enough to form a wrench or key socket, so that the well-known wrench or pinion K may have its end inserted into said socket R, and the teeth of said key will project far enough from the body of the furniture to engage the teeth of the adjacent toothed piece. The piece BB is in all re-

spects similar to piece B, except that it is wider. The beveled sides of the pieces A B are at the same angle relatively to the straight sides. The bolts $b b'$ have their gripping 5 ends beveled on one side only. Now when the pieces A and B or A and BB are assembled, as in Fig. 2, the two pieces together form a rectangle. Should this be too small to fill the place intended, key K may be inserted 10 into socket R and turned in such direction as to move the pieces relatively to each other, and thus bring the two broad ends nearer to each other, expanding the width of the combination-block. One or the 15 other of the catches $b b'$ will engage a tooth on piece A and prevent a backward movement; but by drawing said catch or catches out of engagement the pieces may slide back. It will be understood that if the narrow ends 20 of these two combination-pieces are in proximity to each other; instead of the wide ends, as in Fig. 3, the width of the space occupied by the two pieces will be but little more than the greatest width of the widest one. By 25 having two pieces B BB substantially alike except as to width a considerable latitude of provision for adjustment is provided. The other piece of the combination set is indicated at C. This has both edges at an inclination with the ends. One of the edges is 30 provided with rack-teeth A⁴. The other edge is provided with holding-catches $b b'$. The edge provided with holding-catches has also key-seat R. In fact, all the pieces which have 35 recesses R have them on both faces, so that whichever side up the piece may be it will have a recess in position to receive a locking-wrench, and as the teeth A⁴ extend from top to bottom of the furniture the wrench or key 40 K can be applied so as to engage such teeth whichever side of the furniture is uppermost. It is advisable that the recess R do not extend entirely through the rib at the edge of the furniture-piece to possibly injure 45 the imposing-stone. The double - tapered piece C can be applied between two of the pieces having a single taper or incline, the toothed edge of the piece C engaging the catch on a plane edge piece as BB and the 50 catch or bolts engaging the toothed edge of piece A. Thus a rectangle is formed of three pieces, which may be expanded or contracted by endwise movement of any one of the three pieces.

55 The endwise movement of the furniture may serve to expand the devices for the purpose of filling more space, or such movement may serve as a means of locking up forms. It is desirable to have one edge of the furniture-pieces a plane face, so that longitudinal movement may be not too difficult when that face bears against the chase or against form-plates.

60 It will be seen that a rectangle may be formed from two of the pieces having each a single inclined edge or from three pieces, two of which have each a single inclined

edge and one piece having both edges inclined. A set of furniture might therefore consist of three pieces only; but I prefer to 70 make a set of four pieces, as giving a wider scope for adjustment.

The adaptability of this furniture for the numerous uses of printing-offices has been effectively demonstrated.

75 It must be understood that these furniture blocks or pieces are not inseparably linked or connected together, but one piece may be lifted out of a type-form and another of a different size put in its place whenever there 80 is no edge pressure on the pieces. In this respect the furniture is quite different from several well-known quoins having a somewhat-similar general appearance except as to size, but in which the members constituting the quoin must at all times maintain the same relative position—as, for instance, in the quoin patented to McConnel, No. 326,438, September 15, 1895.

85 What I claim is—

90 1. A set of furniture for printers' use consisting essentially of disconnected pieces free for arrangement in various relative positions, the primary set consisting of two pieces beveled on one side only, and a piece beveled on 95 both sides for use between the two, and positive locking means engaging adjacent pieces to prevent endwise movement, whereby the combined width of the adjusted set may be maintained until the pieces are unlocked, 100 substantially as described.

95 2. A combination printers' furniture consisting of separate and unattached pieces, one of said pieces being wedge-shaped and having a rack on one edge, another piece being wedge-shaped and provided with a spring-bolt projecting at one edge in position to engage said rack on the companion piece, said 105 spring-bolt having one beveled face, whereby the two pieces may be locked as against longitudinal movement, but either may be lifted free from the other, substantially as described.

110 3. In printers' furniture a metallic wedge-shaped piece with generally-vertical edges and having a recess near one edge, of nearly 115 semicylindrical form, serving as a wrench-socket, and having a spring-bolt with beveled end projecting from its side, the piece being adapted for manipulation independently, but specially intended for use in combination 120 with other pieces, substantially as described.

125 4. In printers' furniture, a metallic piece having two mortises containing spring-actuated bolts, the ends of said bolts being connected by a clasp serving as a handle by 130 which they may be withdrawn, substantially as described.

In testimony whereof I affix my signature in presence of two witnesses.
